L. M. DABNEY

FAN

Filed Nov. 6, 1924

FIG. 1.

FIG. 2.

FIG. 3.

Inventor:

Lillian M. Dabney,

F. G. Fischer

Attorney

Witness:

Frederick Fischer.

UNITED STATES PATENT OFFICE.

LILLIAN M. DABNEY, OF KANSAS CITY, KANSAS.

FAN.

Application filed November 6, 1924. Serial No. 748,174.

To all whom it may concern:

Be it known that I, LILLIAN M. DABNEY, citizen of the United States, residing at Kansas City, in the county of Wyandotte and State of Kansas, have invented certain new and useful Improvements in Fans, of which the following is a specification.

My invention relates to improvements in fans for personal use and my object is to provide a novelty of this character which is both artistic and useful, and which may be folded into compact form when not in use.

In order that the invention may be fully understood, reference will now be had to the accompanying drawing, in which:

Fig. 1 is a side elevation of the fan in open position.

Fig. 2 is a vertical sectional view of the fan in folded position.

Fig. 3 is a vertical sectional view of the fan in open position.

Fig. 4 is a detail perspective view of the body portion of the fan in folded position.

Referring now in detail to the different parts, 2 designates a tubular handle open at both ends and which may consist of celluloid or other suitable material. 4 designates the body portion of the fan which may consist of printed Japanese paper or other suitable material. Said body portion is creased at intervals as indicated at 5, so that it may be readily folded into compact form and introduced into the handle 2. The end margins of the body portion 4 are reinforced by a strip of ribbon, tape or other strong material 6, which is pasted or otherwise affixed to said margins.

8 designates a cord tied around the lower end of the body portion 4 to retain said lower end in compact form and also provide a point of attachment for the upper end of a cord 10, which is provided at its lower end with a stop, preferably, in the form of a ring 12.

14 designates a cord or elastic extending through the ends of the reinforcement 6 and attached to stops 16 in the form of ornamental beads, or buttons.

50 In practice the body portion 4 is withdrawn from the handle 2 by the cord or elastic 14 until checked by the ring 12 contacting the lower end of said handle 2, as shown by Figs. 1 and 3. The body portion 4 is then spread to open position by pulling downwardly upon the cord or elastic

14 and engaging the same under the lower end of the handle 2. The fan is now ready for use.

When it is desired to adjust the body portion 4 to inactive position the cord or elastic 14 is disengaged from the lower end of the handle 2. The ring 12 is then pulled downwardly, which operation draws the body portion 4 into the handle 2 until checked by the stops 16 contacting the upper end of said handle. From the foregoing description it will be understood that the stops 12 and 16 prevent the body portion 4 from being entirely withdrawn from either end of the handle 2.

While I have shown and described the preferred form of the invention, I reserve the right to make such changes in the construction, combination and arrangement of parts as properly fall within the spirit and scope of the invention as claimed.

Having thus described my invention, what I claim and desire to secure by Letters Patent, is:

1. In a fan of the character described, a foldable body portion, a tubular element for supporting said body portion while in operative position and into which said body portion may be folded to inoperative position, an elastic attached to the body portion to adjust the same to operative position, and a stop to limit the inward movement of the body portion when the same is drawn into the handle.

2. A fan of the character described consisting of a foldable body portion, a tubular handle supporting said body portion while in operative position and into which said body portion may be folded to inoperative position, a cord for drawing the folded body portion into said handle, a ring at one end of said cord to check the outward movement of the body portion when the same is adjusted to operative position, an elastic attached to said body portion to draw the same outwardly to operative position, and stops secured to said elastic to check the inward movement of the body portion when the same is folded to inoperative position in the handle.

In testimony whereof I affix my signature, in the presence of two witnesses.

LILLIAN M. DABNEY.
